LACE OR THE LIKE

Jack M. Kracke, Flushing, N. Y.

Application November 10, 1948, Serial No. 149,560

Term of patent 7 years

(Cl. D47—6)

To all whom it may concern:

Be it known that I, Jack M. Kracke, a citizen of the United States, residing at Flushing, in the county of Queens and State of New York, have invented a new, original, and ornamental Design for a Lace or the like, of which the following is a specification, reference being had to the accompanying drawing, forming part thereof.

The figure is a plan view of a lace or the like, showing my new design.

I claim:

The ornamental design for a lace or the like, substantially as shown.

JACK M. KRACKE.
